GEAR SHIFT LEVER ASH RECEIVER

Alfred J. K. Wallace, Astoria, Oreg.

Application May 21, 1937, Serial No. 144,065

1 Claim. (Cl. 131—59)

This invention relates to ash receivers, and its general object is to provide an ash receiver for smokers that is primarily designed to be applied to the gear shift lever of a motor vehicle or associated therewith through the knob thereof, now in general use, and is not only capable of receiving ashes, but also for extinguishing burning cigarettes, tobacco and the like, thereby overcoming damage by fire.

10 A further object is to provide an ash receiver that can be in the form of a knob, to be applied to the lever in the same manner as knobs now in general use and has the same appearance and function but includes a receptacle mounted for 15 movement for disposal to open or closed positions, and which is detachable to facilitate removal of its contents.

Another object is to provide a combined lever knob and ash receiver, that is simple in construction, inexpensive to manufacture and extremely 20 efficient in use, operation and service.

This invention also consists in certain other features of construction and in the combination and arrangement of the several parts, to be hereinafter fully described, illustrated in the accompanying drawing and specifically pointed out in the appended claim.

In describing the invention in detail, reference 30 will be had to the accompanying drawing wherein like characters denote like or corresponding parts throughout the several views, and in which:

Figure 1 is a top plan view of the device which forms the subject matter of the present invention.

Figure 2 is a sectional view taken approximate- 35 ly on line 2—2 of Figure 1.

Figure 3 is a vertical sectional view taken at right angles to Figure 2.

Referring to the drawing in detail, it will be noted that the gear shift lever is indicated by 40 the letter A and that my device in the form as shown, includes an outer shell of substantially spherical formation, that is made up of a body section 1 and a cap section 2, the latter being substantially in the form of a ring and is tapered toward its open outer end as shown, while its inner 45 enlarged end is reduced to provide an annular flange 3 and a shoulder 4 providing a seat for the upper end of the body section, which is externally threaded to threadedly receive the flange, for 50 detachably securing the cap section to the body section, as will be apparent.

The body section is shown as being of semi-spherical formation and formed thereon or otherwise secured thereto is a threaded ferrule 5 ex- 55 tending from the center thereof, for the purpose

of securing the device to the gear shift lever A, as shown.

Mounted for movement in the outer shell and for fitting association with the body section 1, is the inner shell 6 of my device, which is likewise of spherical formation and the inner shell is shown as being made of two half or semi-spherical sections having interfitting channel tongues 7 for securing the half sections together, and the tongues provide a rib extending outwardly from 10 and about the circumference of the inner shell as best shown in Figure 3. The body section has a channel groove 8 therein for slidably receiving the rib provided by the channel tongues, therefore it will be obvious that the inner shell is 15 guided in its movement within the outer shell and is held therein by the cap section 2.

The inner shell provides a receptacle as will be apparent, and has an opening 9 therein which is relatively small but of course is of sufficient size 20 to readily receive ashes, as well as burning cigarettes, tobacco and the like for disposal within the receptacle, which as shown in Figures 2 and 3 is disposed with the opening arranged uppermost and concentrically with respect to the open upper end of the cap section, but due to the fact 25 that the inner shell or receptacle is movable, it will be obvious that the opening 9 can be arranged to be closed by the cap section.

From the above description and disclosure of 30 the drawing, it will be obvious that I have provided an ash receiver, within which ashes and the like can be easily deposited when the inner shell or receptacle is disposed in open position, and when it is disposed to closed position it will 35 be apparent that air is excluded from the inner shell, thereby extinguishing burning cigarettes, tobacco and the like in minimum time, which not only overcomes the danger of fire but also prevents the outer shell from becoming hot and un- 40 comfortable when shifting gears.

While I have illustrated an ash receiver as being in the form of a knob to be applied to a gear shift lever, I want it understood that it can 45 be in any form suitable for the purpose and applied to knobs now in general use by suitable securing means, or applied, supported or secured to any means or object, as it is not necessarily confined to a gear shift lever of a motor vehicle, and can be used anywhere desired it of course being understood that the ferrule 6 can be in the form of a flat base or other means for supporting and securing the receiver in position for use.

It is thought from the foregoing description that 55

the advantages and novel features of the invention will be readily apparent.

It is to be understood that changes may be made in the construction and in the combination and arrangement of the several parts, provided that such changes fall within the scope of the appended claim.

What I claim is:

An ash receiver comprising an outer spherical shell having an open upper end, an inner spherical shell providing a receptacle and having a relatively small access and discharge opening therein, said inner shell being made up of two semi-spherical sections having interfitting channel tongues about the meeting edges thereof to provide a circumferentially disposed rib extending

outwardly therefrom, said inner shell fitting within the outer shell and mounted for movement about the center thereof for disposing the opening into and out of registration with the open upper end whereby to open and close the receptacle, said outer shell including a body section and a cap section threadedly secured to the body section to allow removal of the inner shell from the outer shell, said body section having a channel groove therein extending to its upper edges and the rib being slidably mounted in the groove for guiding the movement of the inner shell in a fixed path, and mounting means for the receiver and secured to and depending from the outer shell.

ALFRED J. K. WALLACE.
